[57] CLAIM

The ornamental design for a display cabinet, as shown and described.

DESCRIPTION

FIG. 1 is a top, front, and left side perspective view of a display cabinet showing my new design, the rear and right side being mirror images thereof;

FIG. 2 is a top, front, and left perspective view thereof, in an open condition;

FIG. 3 is a bottom plan view thereof;

FIG. 4 is a top, rear, and right side perspective view thereof;

FIG. 5 is a top, front, and left side perspective view showing an alternate embodiment of FIG. 1; and

FIG. 6 is a rear and left side perspective view thereof the right side being a mirror image thereof.
